CIRCULAR KNITTING MACHINE OF THE
INDEPENDENT NEEDLE TYPEEdward Victor Stibbe and Bert Smith,
Leicester, England.Application November 26, 1947, Serial No. 788,260
In Great Britain December 2, 1946

6 Claims. (Cl. 66—27)

1

This invention relates to circular knitting machines of the independent needle type, and is applicable to multi-feed machines wherein there are adjustable cams in the cam systems for effecting knitting adjustments.

The invention is intended for application primarily to cam systems which are concerned with the control and operation of the needles and include circular series of adjustable cams provided for the purpose of regulation of the length of loops or stitches, for example, to produce knitted fabric of a required quality, or/and as may be required according to the count of the yarn to be used, but the invention is not necessarily limited in this respect as it may be applied to cam systems for producing movements of other loop forming instruments, or instruments which co-operate with the needles in loop formation, such, for example, as loop forming sinkers or holding-down sinkers or web holders, in respect of which adjustment of cams is required for purposes well known in the art. Therefore the expression "cam systems" is used in a generic sense.

In a circular knitting machine of the type concerned with a multiplicity of angularly spaced feeds, e. g. of the order 8, 12, 16 or more, for producing tubular web or body fabric, and with an adjustable cam or cams at or in the region of each feed, individual adjustment of the cams, i. e. separately all round the machine, by manual means, occupies considerable time and commensurately holds up production. Where there are two needle beds, or a cylinder and a dial, or coaxial cylinders, the number of cams is correspondingly higher. For example, there may be as many as 32 cams, comprising knocking-over cams and associated retaining cams in a sixteen feed machine of the cylinder and dial type adapted to produce interlock fabric. Consequently separate adjustment of the cams in a complete circular series is a slow and laborious procedure since the cams are usually attached to screws adapted to be turned by a screw driver, or other suitable hand tool, and a scale or graduation is provided, in conjunction with an index, for each screw, to which the operator has to work.

The present invention comprises an improvement the object of which is to reduce the time and work required for cam adjustment to a minimum, as will be hereinafter described.

Accordingly the invention comprises, in a multi-feed circular knitting machine, the combination with a cam system including a number of adjustable cams, as aforesaid, of mechanism

2

adapted for effecting multiple adjustments simultaneously.

A particular illustrative embodiment of the invention applied to the dial cam systems of a machine of the cylinder and dial type adapted to produce interlock fabric, will now be described with reference to the accompanying drawings, wherein,

Figure 1 is a vertical sectional view of so much of the head of the said machine, showing more particularly the inner and outer dials and the associated dial cam cap, as is necessary to illustrate the application of the invention thereto,

Figure 2 is an underside plan view of a few of the adjoining dial cam cap sections, showing adjustable knocking-over cams and associated adjustable retaining cams of the inner and outer dial cam systems.

Figure 3 is a general perspective view of one of the said dial cam cap sections, as viewed from the underside thereof, showing more clearly the manner in which the knocking-over cams and the associated retaining cams of the two systems are adjusted,

Figures 4, 5, 6 and 7 are detail underside perspective views illustrating the adjustable slides to which the said cams are attached,

Figure 8 is a sectional view of a removable door section of the dial cam cap shown in its relation to a main adjusting pinion hereinafter to be described,

Figure 9 is a detail plan view of portions of the dials, with the door section of the dial cam cap removed to show the adjusting pinion in mesh with an annular indexing gear or toothed ring by means of which and pinions on the adjustable cam slides the latter are geared together,

Figure 10 is a perspective view of the main adjusting pinion and a fragmentary portion of the indexing gear or toothed ring,

Figure 11 is a plan view of a portion of the said gear or ring, and

Figures 12 and 13 are two detail, part-sectional views showing alternative forms of friction spring means for preventing the cam slide pinions from over-running.

Like parts are designated by similar reference characters throughout the drawings.

Referring to Figure 1, it will be seen that the sections S of the dial cam cap 1 are attached, by means of screws 2, to a central dial cap hub 3 by which the entire cap is rigidly secured to a fixed central column (not shown). The reference numeral 4 indicates the rotary dial carrier plate which is centrally bossed at 5 and re-

cessed to receive an outer dial 6 slotted to receive inserted trick wall elements such as 7, and a radially tricked inner dial 8, the said two dials being adapted to receive two respectively different and independently operable sets of dial needles as is conventional practice in a cylinder and dial machine of the interlock type. The periphery of the dial cam cap is recessed to receive a dial needle guard 9, and each of the sections S has attached thereto a feeder bracket 10. The particular machine illustrated is an 8-feeder machine, so that the dial cam cap 1 comprises eight of the adjoining sections S and also a smaller and removable door section S¹. An inverted plan view of a few of the said sections, including the door section S¹, is shown in Figure 2. As depicted in Figure 8 the door section is secured to the hub 3 by a thumb screw 11 and is furnished with a milled knob 12 to facilitate its removal and insertion. The rotary needle cylinder of the machine is indicated in dot-and-dash lines at 13 in Figure 1, the cylinder cam box being shown at 14 and one of the cam posts at 15.

Each section S of the dial cam cap 1 carries on its lower face a knocking-over cam 16, a companion guard cam 17 and a retaining cam 18 incorporated in the outer dial cam system for action on the butts of dial needles accommodated in the outer dial 6, and a knocking-over cam 19, a guard cam 20 and a retaining cam 21 incorporated in the inner dial cam system for similar action on the butts of dial needles in the inner dial 8. In accordance with the present invention the various cams just specified are attached to longitudinally movable slides 22 which are mounted for adjustment radially inwards and outwards within guide channels 23 cut in the underside of the sections S, and are furnished with radially disposed adjusting screws 24 to the inner ends of which are secured pinions 25 arranged in mesh with an annular indexing gear or toothed ring 26. The undersides of the adjustable cam slides 22 are longitudinally channelled at 27 to receive complementarily shaped ribs 28 formed on the cams accurately to locate the latter laterally with respect to the said slides. If desired, certain of the fixed dial cams adjoining the radially adjustable knocking-over, guard and retaining cams may, where convenient, be formed with such ribs in which instance the last mentioned ribs would also assist in guiding the opposed relatively movable slides during radial adjustments thereof. The inner end of each adjustable cam slide 22 is formed with a lateral lug 29 which is tapped to receive the corresponding adjusting screw 24. The leading end of each such screw, i. e. the end thereof remote from the relevant pinion 25, is arranged to make contact with a portion of the dial cam cap as clearly shown in Figures 2 and 3. Each cam slide 22 is controlled by a compression spring 30 which, as shown in Figure 1, is interposed between the back of an upstanding projection 31 provided on the top of the slide and the opposed wall a suitably recessed portion 32 of the dial cam cap formed to accommodate the spring. By reason of this construction, the slides 22 are urged outwardly so that the leading ends of the adjusting screws 24 are maintained permanently in contact with the dial cam cap. In Figure 3 a portion of the dial cam cap section shown is broken away to reveal one of the springs 30. If, therefore, the pinions 25 are simultaneously rotated by turning the annular indexing gear or toothed ring 26, in either direction, the entire circular series of

adjusting screws 24 will be turned within the aforesaid tapped lugs 29 with the result that all of the cam slides 22 will be longitudinally moved, either radially inwards or outwards, to effect corresponding inward or outward adjustments of all of the aforementioned adjustable dial cams simultaneously. For the sake of simplicity and convenience in illustration, the adjusting screws and pinions on one only of the dial cam cap sections S have been shown in Figure 2. As will be appreciated from the foregoing description at least some of the adjustable cam slides 22 will be supported and held up within the guide channels 23 by fixed dial cams attached to the underside of the dial cam cap: but in cases where there are insufficient or even no fixed cams underlying a cam slide, then that slide may be retained in its guide channel 23 by a retaining screw, such as 33 (see the right-hand side of Figure 1) which is screwed into a tapped hole formed to receive it in the upstanding projection 31 on the top of the slide. The limit of the outward movements of the adjustable cam slides is determined by the sectional dial needle guard 9.

With regard to the annular indexing gear or toothed ring 26, this is freely mounted for turning movement within a circumferential recess 34 formed beneath and at the periphery of the dial cap hub 3 and is held up in position by a retaining ring 35 attached to the lower face of the said hub by means of screws 36. The upper surface of the gear or toothed ring 26 is cut with teeth 26¹ for meshing with the pinions 25 and also with a main adjusting pinion 37 by means of which latter the said gear or toothed ring is turned one way or the other. To enable this to be done, the pinion 37 is fitted with an adjusting nut 38 or an equivalent single member for manual operation. For example, in lieu of a single member formed with flats for reception of a spanner, a wheel or knob may be adopted, this being milled or knurled for engagement directly by hand, or formed with holes to receive a tommy bar. In any event, the nut 38 or other single member is normally covered by the removable door section S¹ of the dial cam cap which is cut away at 39 (see Figures 2 and 8) to clear it. The pinion 37 and the associated nut 38 are mounted for rotation upon a plain portion of a screw which is screwed into the hub 3 as shown in Figure 8.

As shown in Figure 11, a relevant portion of the indexing gear or toothed ring 26 has formed therein an endmilled recess 40, the bottom of which is graduated and stamped or otherwise marked with numbers accurately disposed in relation to the roots of the teeth 26¹. When turning the gear or toothed ring 26 these numbers 41 are used, in relation to a zero mark or index made on a part of the dial cap hub 3. This part is recessed, as shown at 42 in Figures 9 and 10, to reveal a few, e. g. three, only of the numbers. Numbers to the right of the zero mark are used 43 to give an "on" adjustment whilst those to the left of the said mark give an "off" adjustment, it being understood that the numbers bear a relation to and indicate predetermined degrees of adjustment of the cams. Thus, to effect simultaneous adjustment of all of the dial cams concerned, the thumb screw 11 is first taken out, to permit removal of the door section S¹ by means of the milled knob 12, whereupon the main adjusting pinion 37 is turned by the application of a spanner to the associated nut 38 so as to effect a

turning movement to the desired extent of the indexing gear or toothed ring 26 by which and the pinions 25 the adjusting screws 24 are geared together as previously explained.

To prevent the pinions 25 from over-running or tending to move when not required to do so, friction spring or equivalent means are arranged to bear upon any appropriate parts of the pinions. In the example illustrated in Figure 12, an appropriately fashioned double-ended blade-spring 43 is attached centrally between its ends to the underside of the dial cam cap 1, by means of a single screw 44, the free end portions of this spring being curved to embrace and frictionally engage a few teeth of a pair of adjacently disposed pinions 25. The pinions of each successive pair throughout the circular series are similarly controlled by a double-ended blade-spring. An alternative and more simple form of friction spring is shown at 45 in Figure 13.

It will be noted that each of the aforementioned guard cams is adjustable radially in company with its associated knocking-over cam. To enable this result to be achieved each guard cam is rigidly attached to the slide 22 to which the corresponding knocking-over cam is attached, so that at all times and even upon adjustment of the slide the two cams will bear the same relation to each other. This is an important feature and in contradistinction to customary practice in which, upon adjustment of a knocking-over cam, the associated guard cam remains relatively stationary. By adjusting both of such cams in company the butts of dial needles which are retracted at a knocking-over point are immediately and positively restored to the non-knitting track, thereby preventing the production of lines and other undesired effects in the fabric. Thus, needle butts acted upon by a cam 16 will be positively restored by the cam 17 to the non-knitting track 46 (Figure 2), whilst butts acted upon by a cam 19 will be similarly restored by the associated cam 20 to the non-knitting track 47.

An embodiment of the invention similar to that described may alternatively be applied to the cylinder cam system, or both to the dial cam system and the cylinder cam system of a machine of the cylinder and dial type adapted to produce interlock fabric. With a cylinder cam system an externally toothed ring may be located in a vertical recess in the inner face of the cam box or shell, and the adjusting screws may be mounted vertically in the box or shell with their pinions disposed horizontally in engagement with the external teeth of the ring, for vertical adjustment of the cams. In either arrangement an index for use in conjunction with the teeth or graduations on the gear or the ring, as already described is provided adjacent to the master adjusting unit, or an independent scale with an index may be adopted, to facilitate adjustment of the cams to the required degree.

As will be appreciated, by suitable modification as to arrangement of the parts a similar embodiment of the invention may be applied to a cam system for controlling and operating sinkers, web holding sinkers or other yarn engaging instruments co-operative with needles in loop formation.

In addition to obviating the disadvantage hereinbefore mentioned, the invention is advantageous in that the possibility of inequalities attendant upon individual adjustment of cams and corresponding variations in the quality of the knitted fabric is practically eliminated.

Instead of screws interconnected by means of pinions and a common annular gear or toothed ring, interconnecting means, such as levers and links or flexible members, e. g. of the Bowden wires type, connected to a common operating member may be employed. When, as may be, the cam systems include pivotal cams, toothed segments may be substituted for screws, or the cams may be attached respectively to levers and linkage or flexible members connected to a common operating member may be adopted for effecting adjustments.

If desired, the collective adjustment of the selected cams may be effected automatically, at a required time, as by operation from a convenient power driven member of the machine, e. g. on the control shaft, or from the timing chain through appropriate intermediate connections.

While the invention is applicable primarily to 20 multi-feed circular knitting machines of the cylinder and dial type for producing interlock fabric, and employing numerous adjustable cams in the knitting cam systems, it may be applied to machines of the same type for producing ordinary rib fabric, to multi-feed circular plain knitting machines, and to multi-feed machines of the double-axially opposed needle cylinder type, for example, those equipped with superimposed needle cylinders and double-ended needles operated through the medium of sliders, all of which machines are adapted for producing body fabric for manufacture subsequently into articles of clothing, or for producing body garments or garment lengths. The invention is also capable of application to smaller multi-feed machines for producing stockings and like articles, wherein cam adjustment to give definite, or variations in, stitch length may be a desideratum.

It will be appreciated that in some circular knitting machines the cam systems act directly on the needles and co-operative elements, if provided, whereas in others the cam systems act through the medium of jacks, to produce the knitting movements, and that the invention accordingly is applicable to both cases.

What we claim then is:

1. In a circular knitting machine, in combination, a series of independent loop forming instruments, a multiplicity of angularly spaced feeds, a cam system including at least one adjustable cam at each of said feeds for effecting movements of the said loop forming instruments, members to which said cams are attached, screws for adjusting the said members, pinions on the screws, a common annular indexing gear with which the said pinions are arranged in mesh, and means for turning the said indexing gear and thereby effecting simultaneous adjustment of the aforesaid cams.
2. In a circular knitting machine, in combination, a series of independent loop forming instruments, a multiplicity of angularly spaced feeds, a cam system including at least one adjustable cam at each of said feeds for effecting movements of the said loop forming instruments, members to which said cams are attached, screws for adjusting the said members, pinions on the screws, a common annular indexing gear with which the said pinions are arranged in mesh, and, for turning the said indexing gear, a master pinion which is fitted with a single member for manual operation, for the purpose herein described.
3. A combination according to claim 2, wherein the master pinion is combined with an adjusting 75 nut having flats for reception of a spanner.

4. In a circular knitting machine, in combination, a series of independent loop forming instruments, a multiplicity of angularly spaced feeds, a cam system including at least one adjustable cam at each of said feeds for effecting movements of the said loop forming instruments, members to which said cams are attached, screws for adjusting the said members, pinions on the screws, a common annular indexing gear with which the said pinions are arranged in mesh, means for turning the said indexing gear and thereby effecting simultaneous adjustment of the aforesaid cams, and an index for use in conjunction with the teeth of the indexing gear to facilitate adjustment of the cams to the required degree.

5. In a circular knitting machine of the cylinder and dial type adapted to produce interlock fabric, in combination, a dial, two sets of dial needles in said dial, a multiplicity of angularly spaced feeds, inner and outer dial cam systems each including knocking-over cams and associated retaining cams at the respective feeds for effecting movements of the dial needles, spring-controlled adjustable slides to which the said cams are attached, adjusting screws on the slides, pinions secured to the said screws, a common annular indexing gear with which the pinions are arranged in mesh, and a master adjusting pinion which is also arranged in mesh with the gear and fitted with a single member for manual operation, the construction and arrangement being such

that operation of the said means effects collective adjustment of the cams.

6. In a circular knitting machine, in combination, a series of independent loop forming instruments, a multiplicity of angularly spaced feeds, a cam system including at least one adjustable cam at each of said feeds for effecting movements of the said loop forming instruments, spring-controlled adjustable slides to which the said cams are attached, adjusting screws on the slides, pinions secured to the said screws, a common annular indexing gear with which the pinions are arranged in mesh, and a master adjusting pinion which is also arranged in mesh with the gear and fitted with a single member for manual operation, the construction and arrangement being such that operation of the said means effects collective adjustment of the cams.
